Primary Examiner — Catherine Ho*(74) Attorney, Agent, or Firm* — Chun-Ming Shih;
 Lanway IPR Services(57) **CLAIM**

The ornamental design for a cabinet, as shown and described.

DESCRIPTION

FIG. 1 is a perspective view of a cabinet showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of encircled area 8 in FIG. 1;

FIG. 9 is an enlarged view of encircled area 9 in FIG. 4; and,
 FIG. 10 is an enlarged view of encircled area 10 in FIG. 5.
 The broken lines show portions of the article that forms no
 part of the claimed design.
1 Claim, 10 Drawing Sheets(56)
